N°4716

UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 19,348, dated October 8, 1889.

Application filed September 10, 1889. Serial No. 323,558. Term of patent 3½ years.

To all whom it may concern:

Be it known that I, WILLIAM McCALLUM, a citizen of the United States, residing at Yonkers, Westchester county, New York, have 5 invented a new and original Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and the border B. The body A contains large figures having irregular outlines and containing flower and leaf forms and other ornaments 20 of various characters. These figures are mainly arranged in groups. The background is composed of a curved-line ornamentation.

The border B has an inner margin consisting of a row of ornaments and an outer margin containing various ornamental figures. Between the margins are large figures having irregular outlines, mainly arranged in groups, and containing flower and leaf forms and other ornaments of various characters; and the background is composed of a curved-line 30 ornamentation.

What I claim as new, and desire to secure by Letters Patent, is—

1. A design for carpets, consisting of the body A, substantially as shown. 35
2. A design for a carpet, consisting of the border B, substantially as shown.
3. A design for carpets, consisting of the body A and border B, substantially as shown.

WILLIAM McCALLUM.
